CLAIM

The ornamental design for a network extender, as shown and described.

DESCRIPTION

FIG. 1 is a front perspective view of the network extender according to the present design in a first embodiment; FIG. 2 is a front elevational view of the network extender of FIG. 1;

FIG. 3 is a rear elevational view of the network extender of FIG. 1;

FIG. 4 is a left-side elevational view of the network extender of FIG. 1;

FIG. 5 is a right-side elevational view of the network extender of FIG. 1;

FIG. 6 is a top plan view of the network extender of FIG. 1; FIG. 7 is a bottom plan view of the network extender of FIG. 1;

FIG. 8 is a front perspective view of the network extender according to the present design in a second embodiment; FIG. 9 is a front elevational view of the network extender of FIG. 8;

FIG. 10 is a rear elevational view of the network extender of FIG. 8;

FIG. 11 is a left-side elevational view of the network extender of FIG. 8;

FIG. 12 is a right-side elevational view of the network extender of FIG. 8;

FIG. 13 is a top plan view of the network extender of FIG. 8; and,

FIG. 14 is a bottom plan view of the network extender of FIG. 8.

The broken lines showing in the figures illustrate portions of the network extender that form no part of the claimed design.
